JOHN F. O'CONNOR, OF CHICAGO, ILLINOIS, ASSIGNOR TO WILLIAM H. MINER, OF CHAZY,
NEW YORK.

SPRING-GEAR.

1,300,470.

Specification of Letters Patent. Patented Apr. 15, 1919.

Application filed February 16, 1918. Serial No. 217,509.

To all whom it may concern:

Be it known that I, JOHN F. O'CONNOR, a citizen of the United States, residing at Chicago, in the county of Cook and State 5 of Illinois, have invented a certain new and useful Improvement in Spring-Gears, of which the following is a full, clear, concise, and exact description, reference being had to the accompanying drawings, forming a 10 part of this specification.

This invention relates to improvements in spring gears.

One object of the invention is to provide an exceedingly simple arrangement of tandem spring gear for railway cars, which tandem gear may be conveniently located in the relatively short spacing now utilized for friction gears.

Another object of the invention is to provide 20 a tandem spring gear in which the use of a thimble in the yoke is avoided and also wherein the ordinary stop lugs may be used instead of the more expensive and heavier cheek plates.

25 In the drawing forming a part of this specification, Figure 1 is a horizontal, sectional view of a portion of a railway draft rigging showing my improvements in connection therewith. Fig. 2 is a transverse, 30 vertical, sectional view, taken substantially on the line 2-2 of Fig. 1. And Fig. 3 is a detail perspective view of one of the blocks employed in my invention.

In said drawing, 10-10 denote channel-shaped center or draft sills of a railway car, to the inner faces of which are secured ordinary stop lugs 11-11 arranged in front and rear sets in a well known manner, the spacing between the front and rear sets of stop 40 lugs being 24 $\frac{5}{8}$ ", as illustrated in the drawing, which is the usual spacing for modern friction draft riggings and which, as is well known, is considerably less than the standard spacing between the front and rear sets 45 of usual tandem arranged stops.

In my improved gear, I employ front and rear followers 12 and 13 between which the shock absorbing unit is placed and operatively connect the same with the draw bar 50 14 by an ordinary yoke 15, the latter having no central thimble, as will be apparent. All the parts are supported in any suitable manner as by the detachable saddle plate 16.

The improved shock absorbing unit includes a pair of springs 17-17, which may

be of the so-called class "G" type; and a pair of blocks 18-18. Each of the blocks 18 has an outer end 19 adapted to bear against the adjacent follower, a curved spring seat 20 extending longitudinally of 60 the block, and an inward extension 21 adapted to bear against the end of the spring in alinement therewith. The end 21 is extended laterally so as to bear the full width of the spring by means of a triangular extension 65 22 suitably braced by a web 23, as clearly illustrated in Figs. 1 and 3. The two blocks 18-18 are arranged as shown in Fig. 1, that is, one on each side of the gear and the spacing between the inner ends 21 and the 70 opposed transverse shoulders 24 is made equal to the permissible movement of the gear or compression of the spring. In addition to the foregoing, each of the blocks 18 is provided with a cylindrical lug or extension 75 25 at its inner end on which is adapted to be seated the corresponding spring.

As will be evident from the foregoing each block 18 forms a spring seat and guide 80 for one spring and acts as a thrust or column member against the end of the other spring, the two springs being offset laterally. Over-compression of the springs is prevented by the integral limiting stops formed on the blocks, as hereinbefore described, and it is evident also that the extensions or lugs 25 may be of such length as to engage the opposed followers 12 and 13 simultaneously with the engagement of the walls 21 and shoulders 24 of the blocks. 90 The offsetting of the springs and blocks permits of a short tandem gear, and at the same time eccentric resistance to the pressure on the followers is obviated since both springs are compressed simultaneously and the center of pressure or resistance for each spring is comparatively near the center line of the gear. The blocks 18 may be cored, as indicated most clearly in Fig. 3, to decrease the amount of material required, while at 100

the same time leaving all the strength necessary. It is also apparent that the blocks support the springs without the necessity of employing separate members for this purpose so that the entire shock absorbing unit 105 is comparatively cheap to manufacture and eliminates many of the difficulties heretofore encountered in the use of the usual type of tandem spring gears wherein the yoke has required an intermediate thimble.

I claim:

In a tandem spring gear, the combination with draft sills having front and rear sets of stop lugs and front and rear followers; 5 of a pair of oppositely arranged blocks interposed between said followers, each block having an outer end arranged to be engaged by the adjacent follower, a longitudinally extending spring seat, an intermediate transversely extending shouldered portion, and an inner transversely elongated end reinforced by a diagonal bracing wall; and tandem arranged springs laterally offset from each other, each spring being seated in the spring

seat of one block and its inner end engaging 15 the inner end of the other block, a portion of the transversely elongated inner end of each block being in line with the intermediate transverse shouldered portion of the other block and normally spaced therefrom, 20 said blocks being arranged to come into contact upon actuation of the gear to thereby limit the compression of the springs.

In witness that I claim the foregoing I have hereunto subscribed my name this 25 7th day of Feb., 1918.

JOHN F. O'CONNOR.
